CLAIM

The ornamental design for a lap splice coupler for concrete reinforcing members, as shown and described.

DESCRIPTION

FIG. 1 is a top perspective view of the lap splice coupler for concrete reinforcing members;

FIG. 2 is a bottom perspective view of the lap splice coupler for concrete reinforcing members;

FIG. 3 is a top plan view of the lap splice coupler for concrete reinforcing members;

FIG. 4 is a bottom plan view of the lap splice coupler for concrete reinforcing members;

FIG. 5 is a front side elevation view of the lap splice coupler for concrete reinforcing members;

FIG. 6 is a rear side elevation view of the lap splice coupler for concrete reinforcing members;

FIG. 7 is a right side elevation view of the lap splice coupler for concrete reinforcing members; and,

(Continued)

FIG. 8 is a left side elevation view of the lap splice coupler for concrete reinforcing members.

1 Claim, 8 Drawing Sheets
